(57) CLAIM

The ornamental design for a combined food smoker and grill, as shown and described.

DESCRIPTION

FIG. 1 is a left side elevational view of a combined food smoker and grill showing my new design;

FIG. 2 is a right side elevational view thereof;

FIG. 3 is a perspective view looking from the right rear thereof;

FIG. 4 is a rear elevational view thereof;

FIG. 5 is a front elevational view thereof; and,

FIG. 6 is a bottom plan view thereof.

The details shown in broken lines in all views are for illustrative purposes only and form no part of the claimed design.
